CHARLES W. JONES, OF ST. PAUL, MINNESOTA

SAFETY RAZOR.

1,408,355.

Specification of Letters Patent. Patented Feb. 28, 1922.

Application filed April 21, 1920. Serial No. 375,560.

To all whom it may concern:

Be it known that I, CHARLES W. JONES, a citizen of the United States, residing at St. Paul, in the county of Ramsey and State of Minnesota, have invented certain new and useful Improvements in a Safety Razor, of which the following is a specification.

This invention relates to a safety razor of the hoe shaped type.

10 Another object is to provide a razor of this character having a two edged blade with an unsharpened extension at one end to permit the blade to be handled without danger of cutting the fingers.

15 Another object is to provide a one-piece frame, for a razor of this character having an offset handle positioned so that the user's fingers will not come in contact with the lather.

20 Another object is to provide a safety razor frame having guards so constructed and arranged that while protecting the blade, they will have a tendency to stretch the skin before the blade reaches the hair, so that a close shave may be obtained.

Another object is to so construct such a razor that it may be sterilized by dipping it in hot water, it being necessary to wipe off the blade only.

30 Another object is to so construct such a razor that it will cut with a slicing instead of a scraping movement.

Another object is to provide such a razor, the blade of which is held firmly in place by bending thereof and insertion of its ends under lugs on the holder.

In the accompanying drawings:—

Figure 1 represents a side elevation of the razor constructed in accordance with this invention.

Fig. 2 is a bottom plan view thereof with parts broken out; and

Fig. 3 is a transverse section taken on the line 3—3 of Fig. 1.

45 In the embodiment illustrated the razor constituting this invention comprises a holder and a blade having cooperating means for detachably connecting them. The holder is composed of a plate 1 slightly curved longitudinally and having extended at right angles from its rear face at one end an edge-wise disposed plate 2 preferably made integral therewith. This plate 2 may be used as a hand grip by persons who desire to operate the razor in that manner.

The plate 2 is provided with a rearwardly projecting longitudinal extension 3 preferably formed integral with the plate 2 at a point intermediate the height thereof. This extension 3 provides an offset handle so that the fingers of the user will not come in contact with the lather on his face while shaving.

Arranged along opposite side edges of the plate 1, are two parallel bars 4, secured at one end to the plate and free at their other ends and which are adapted to receive a rubber covering in the form of tubes 7 which are mounted on the bar 4 present a smooth soft surface to the user's face and have a tendency to stretch the skin before the blade reaches the hair so that a close shave may be obtained.

The front face of the body member or plate 1 of the holder has a rib 5 extending transversely thereof midway its ends and is designed as a support for the razor blade 8 to assist in holding said blade under tension when inserted in the holder, said rib cooperating with inturned lugs 6 at the opposite ends of the holder under which the ends of the plate 8 are inserted as is shown clearly in Fig. 2.

The blade 8 which is composed of thin sheet steel has its opposed side edges sharpened for cutting purposes and is provided at its rear end at one corner with a longitudinal extension and the edges of which are unsharpened, so that it may be used for handling the blade and prevent all danger of cutting the user's fingers. This extension 9 also operates as a stop for limiting the insertion of the blade under the lugs 6 and cooperates with a notch 10 formed in the other end of the blade and which engages the lug 6 at the front end of the holder.

The notch 10 and the extension 9 are preferably so formed that when the blade 8 is inserted as is shown in Fig. 2, the cutting edges thereof will be positioned at a slightly oblique angle, so that the razor will cut with a slicing, instead of a scraping motion.

When the blade 8 is applied to the holder it is bent longitudinally to conform to the curvature of the face of the plate 1 and the ends thereof are inserted under the lugs 6 so that the intermediate portion of the blade bearing on the rib 5, will cause said blade to be held under tension on the holder and all danger of its becoming accidentally dis-

placed is prevented. It will be seen that the handle or finger 9 of this blade will greatly facilitate the handling thereof without danger of cutting the user's fingers.

5 The holder of this razor is preferably constructed of aluminum and constitutes a one-piece structure and being made of aluminum, it may be sterilized or cleaned by simply dipping it in hot water and the necessity of wiping it off is avoided. The only part to be 10 wiped dry is the steel blade 8.

From the foregoing description, taken in connection with the accompanying drawings, the advantages of the construction and the 15 method of operation will be readily apparent to those skilled in the art to which the invention appertains and while I have described the principle of operation of the invention together with the device which I now 20 consider to be the best embodiment thereof

I desire to have it understood that the device shown is merely illustrative and that such changes may be made as are within the scope of the claimed invention.

What is claimed is:—

25 A safety razor comprising a longitudinally curved plate equipped with bars at its opposite edges, rubber tubes covering said bars, each bar being unconnected at one end to permit its rubber tube to be slipped on and off, a handle secured to said plate, and 30 blade receiving means carried by the front face of said plate.

In testimony whereof I affix my signature in presence of two witnesses.

CHARLES W. JONES.
